by his Attorney, Phillips Abbott.

UNITED STATES PATENT OFFICE.

PAUL GUMBINNER, OF NEW YORK, N. Y.

DEVICE FOR STOPPING RUNAWAY HORSES.

SPECIFICATION forming part of Letters Patent No. 323,868, dated August 4, 1885.

Application filed July 1, 1885. (No model.)

To all whom it may concern:

Be it known that I, PAUL GUMBINNER, a citizen of the United States, and a resident of New York city, in the county of New York and State of New York, have invented certain new and useful Improvements in Devices for Stopping Runaway Horses, of which the following is a specification.

My invention relates to a new and useful device attached to buggies, cabs, carriages, and the like vehicles, whereby refractory or runaway horses may be readily restrained without the physical exertion necessary on the part of the driver by the use of the reins only; and it consists in attaching to the vehicle an automatically-acting "take-up" mechanism, to which supplemental reins are attached, and which, being operated upon by the foot of the driver at the desired time, will enable him to control the horse by means of the supplemental reins and the take-up device, leaving the reins which the driver holds in his hands as means whereby the horse may be further controlled and also guided as desired.

In the drawings like letters indicate like parts.

Figure 1 is a side view of a wagon with my invention attached. Fig. 2 is a front view of the same. Fig. 3 is a side view of the double ratchet-wheel at the end of the drum of the take-up device. Fig. 4 are views of the double ratchet-wheel separated into two parts for the purpose of showing the construction of the two halves of the ratchet-wheel more perfectly. Fig. 5 is an edge view of the ratchet-wheel and its locking-pawl.

A is the vehicle; B, the shaft. C is a drum, which may be made of metal, wood, or other suitable material, which is supported on the bottom of the front part of the vehicle by brackets D D. At one end of the drum is attached a double ratchet-wheel, E, which is constructed as shown in Figs. 3 and 4—that is to say, there are practically two ratchet-wheels attached together concentrically. In one the teeth have a forward pitch and in the other a backward pitch, as shown in Figs. 3 and 4. These two wheels are rigidly attached together, and are also rigidly attached to the drum C concentrically. The drum turns upon a shaft, F, which journals in the lower portion of the brackets D D. At one end, and pref-

erably the end upon which the double ratchet-wheel E is fastened, a heavy spring, G, is attached to the shaft F by one end, and by its other end to the bracket D, so that the spring normally will tend to revolve the drum C backwardly, when the pawl, hereinafter to be described, is released from the engagement of the ratchet-wheels E, the operation of the spring being the same as is well known in structures of this character.

Above the double ratchet-wheel E is placed a double-ended pawl, H, (best seen in Figs. 3 and 5.) This pawl is hung upon a pin, I, which is connected with the bracket D, so that the pawl can freely pivot on the said pin I, and one end of this pawl (seen at i in Fig. 3) is made heavier than the other end, i', so that it normally tips with the end i downwardly, and engages with the teeth of that half of the ratchet wheel E which is shown at E² in Fig. 4, thus preventing the action of the spring to turn the drum C until this pawl is lifted.

It should be remarked that the pawl H is bent or set off at its central part, so that the ends i in Fig. 3 will engage with the wheel E² in Fig. 4, and the part marked i' in Fig. 3 will engage with the wheel marked E' in Fig. 4. This is best seen in Fig. 5.

K is a pedal-bar, to be operated upon by the foot of the driver. It rests on its lower end on a plate, L, Fig. 3, or a flattened portion of that part of the pawl H, somewhat to the right of the pivot, upon which the pawl turns, so that pressure being applied by the foot of the driver upon the top of the pedal-bar K, the pawl will be turned upon its pin I, and the other end of the pawl will be brought into engagement with the wheel E'.

M is a guard for the treadle K, placed inside of the carriage, so that the driver will not accidentally tread upon the treadle K. This may be constructed in a number of ways, either to be tipped back on a hinge to expose the treadle, or it may be open at its front end, as at M, Fig. 1, through which opening the driver may insert the toe of his boot.

N are the supplemental reins, which are attached at one end to the drum C, and at the other end to the sides respectively of the bit in the horse's mouth, the lines extending down each side of the horse.

In order to release the horse from the restraint of the apparatus, and also to wind up the spring for second use, I attach to the end of the shaft of the drum C, opposite the 5 ratchet-wheel, a level gear-wheel, O, which matches into another gear-wheel, P, on the end of a vertical shaft, Q, which is supported and turns in a suitable journal box or boxes attached to the bottom of the vehicle, and to 10 the upper end whereof is attached a crank, R. The operation is as follows: Normally the 15 reins N are loose, and the horse has free movement, not being at all controlled by these lines N, and is driven in the usual manner. The end i of the pawl H, being in engagement with the wheel E², prevents the 20 spring G from rotating the drum. Should the horse become refractory or show a disposition to run away, the driver depresses the 25 pedal K, which causes the pawl H to rock on its pivot, thus releasing the wheel E². The spring immediately rotates the drum C and takes up the slack of the supplemental reins N. The end i' of the pawl H also engages at 30 this time with the other wheel, E', which holds the drum against rotation under the pull of the horse, thus tending to hold the horse more firmly, and the driver can further pull in the horse, jamming the wagon close 35 down onto him, and by operating the treadle can take up the slack which he thus gains by pulling in the horse on the drum C, in this way so firmly binding the horse by these supplemental lines N, plus the control he has over him by the ordinary driving-reins, that he will have no difficulty in controlling the horse, however refractory. After the horse 40 has come under control, the restraint of the supplemental reins N is released by depress-

ing the pedal-bar and winding up the spring 40 by the crank R, acting on the drum through the shaft Q and gear-wheels P and O. This action also unwinds the reins, which have been coiled up on the drum, and restores all things to their normal state again, ready for 45 further use.

I do not limit myself to the details of construction shown, for it will be apparent to any one familiar with this art that they may be varied considerably and still my invention be 50 embodied.

I claim—

1. The combination, with a vehicle, of rotatable drum C, spring G, pawl H, ratchet-wheel E, treadle-bar K, and reins N, substantially 55 as and for the purposes set forth.

2. The combination, with a vehicle, of rotatable drum C, double-acting ratchet-wheel E' E², double-acting pawl H, and treadle-bar K, substantially as and for the purposes set 60 forth.

3. The combination, with a vehicle, of rotatable drum C, spring G, ratchet-wheel E, pawl H, treadle-bar K, and guard M, and supplemental reins N, substantially as and 65 for the purposes set forth.

4. The combination, with a vehicle, of rotatable drum C, spring G, ratchet-wheel E, pawl H, treadle-bar K, crank R, shaft Q, and wheels P and O, substantially as and for the 70 purposes set forth.

Signed at New York, in the county of New York and State of New York, this 27th day of June, A. D. 1885.

PAUL GUMBINNER.
